CLAIM

The ornamental design for the combination camera bracket and camera as shown and described.

DESCRIPTION

FIG. 1 is a perspective view of a combination camera bracket and camera showing our new design;

FIG. 2 is a perspective view thereof;

FIG. 3 is a front view thereof;

FIG. 4 is a rear view thereof;

FIG. 5 is first side view thereof;

FIG. 6 is a second side view thereof;

FIG. 7 is a bottom view thereof; and,

FIG. 8 is a top view thereof.

The broken lines illustrate portions of the combination camera bracket and camera that form no part of the claimed design.

1 Claim, 8 Drawing Sheets
